UNITED STATES PATENT OFFICE.

LOUIS M. BARMAN, OF HOLBORN, LONDON, ENGLAND, ASSIGNOR TO RONEO LIMITED,
OF LONDON, ENGLAND, A COMPANY OF GREAT BRITAIN.

INKING DEVICE OR ATTACHMENT MORE PARTICULARLY FOR USE WITH ADDRESSING MACHINES.

1,411,398.

Specification of Letters Patent.

Patented Apr. 4, 1922.

Application filed November 10, 1920. Serial No. 423,092.

To all whom it may concern:

Be it known that I, LOUIS MAURICE BARMAN, a citizen of the United States of America, residing at 5 Holborn, London, E. C., 1, England, Great Britain, have invented certain new and useful Improvements in an Inking Device or Attachment More Particularly for Use with Addressing Machines, of which the following is a specification.

This invention relates to an improved inking device or attachment more particularly for use with addressing machines of the type wherein stencil cards are employed.

In addressing machines of this class the envelopes, labels, or the like are required to receive imprints in imitation of type-written matter, and it is therefore important, when stencils are used, that the quantity of ink forced through each stencil should be carefully considered and so regulated that sharp and clear impressions are produced.

The present invention has for its object to provide an inking device or attachment whereby these features are attained, and for such a purpose an ink container is provided with a wick or wicks and suitable ink filling means.

The container is provided with means whereby it can be raised or lowered into or out of contact with one of a set of ink distributing rollers, and the said distributing rollers are also arranged so that an upward or downward movement may be afforded thereto in such a manner that one of the distributing rollers is operated upon by a member which receives ink therefrom and forces the ink so received through the perforated stencil on to an envelope, label, or the like fed to the machine.

Furthermore, one of the ink distributing rollers has secured thereto an operating handle so that ink may be distributed thereby from the other ink distributing rollers without necessitating a fresh supply of ink from the ink container.

The invention will now be fully described with reference to the accompanying drawings, whereon:

Fig. 1 shows in plan view part of an addressing machine embodying the present invention.

Fig. 2 is a front view.

Fig. 3 is a detail side view showing the

parts as they appear when ink is being supplied from the container.

Fig. 4 is a detail side view showing the inking device in the inoperative position.

The addressing machine is provided with the usual hopper or magazine for receiving the stencil cards, and comprises two standards 1, 1^a, secured to the bed or base 2 of the machine. Beneath the hopper is situated the slideway or track 3 (Fig. 2.) and within this slideway works a reciprocating pusher member (not shown) which acts upon the lowermost stencil card, removes it from the pile, and positions it for printing. The extremity of the slideway receives a container 70 for the used stencils.

The envelopes, labels, or the like are placed on a sliding tray or platform 4 and are moved into position for printing beneath the slideway 3 and stencil therein by 75 means of the hand lever 5.

The bed plate or base 2 is bored out for the reception of the shaft 6 which has secured thereon a spur wheel 7 operated by the handle 8. The shaft also carries a segmented inking roller 9. Spur wheel 7 drives a pinion 10 secured on a shaft 11, and secured to this shaft is a segmented pressing roller 12 (Fig. 2.) which presses the envelope and the stencil card against the segmented inking roller 9. Pinion 10 drives a further pinion 13 (Fig. 4) the shaft of which is cranked to afford a reciprocating movement to the pusher member working in the slideway.

Secured to the standard 1 are a pair of brackets 14 which support a rock shaft 15, and said shaft has a lever 16 thereon which carries a tray or platform 17 supporting the ink container 18 with its wick or wicks 95 and filling means. Rock shaft 15 has also secured thereon a lever 19 the end of which is pivotally connected to a rod 20 supported in a bearing 21 secured to standard 1. The free end of rod 20 contacts against one or other surfaces of a cam 22 secured on a rock shaft 23 supported by the brackets 24, and the end of shaft 15 has secured thereon a lever 25 operated by a slide 26 having a slot 27 therein movable on a pin 28 or stud 100 screwed or otherwise fastened to the standard. The slide is provided with a knob for hand operating.

The brackets 24 also accommodate a spindle 29 supporting a pair of arms 30, said 110

arms carrying at their extremities an ink distributing roller 31 which may be provided with a rubber outer surface, and this roller is in contact with a felt covered distributing roller 32 also carried by arms 30. Roller 32 is likewise in contact with a felt covered roller 33 carried in lugs projecting from said arms and said roller 33 receives the ink from the container 18 by rubbing 10 contact with the wick or wicks therein in a manner presently to be described.

The arms 30 are provided with a spacer bar 34 which also acts as a support for the arms. Situated beneath the spindle 29 and 15 secured to the standard 1 is a stud having a collar or sheath 35 thereon fashioned with a cam surface 36 which forms one seat for the spacer bar or support 34. Secured to collar 35 is a hand lever 37 which can be moved in a right or left hand direction across the surface of the standard, the movement in either direction being limited by the 20 stops 38. The ink distributing roller 31 has secured to its spindle a handle 39.

25 The operation of the inking devices is as follows:—Upon upward pressure being applied to the knob on the slide 26 the lever 25 rocks the shaft 23, the cam 22 acts upon the free end of the rod 20 and depresses it 30 as well as the lever 19 pivoted thereto. This action rocks the shaft 15 with its lever 16 carrying the tray 17 and so raises the ink container 18 into the operative position.

35 The ink distributing rollers 31, 32 and 33 are brought into their operative positions as follows:—

Movement of the hand lever 37 to the left causes the cam surface 36 of sheath 29 to be moved away from the spacer bar or support 40 thereby lowering the arms 30. The position of the parts is now as shown in Fig. 3, wherein the roller 33 is contacting against the wick or wicks of the ink container 18 and the roller 31 is in the position for applying 45 ink to the segmented inking roller 9. Roller 31 is set in motion by turning the handle 39 whereby rollers 32 and 33 are rotated so that the ink collected by roller 33 is distributed by roller 32 to 31. When sufficient ink has been 50 imparted to the distributing rollers the ink supply is cut off by pressing down the knob so that the ink container assumes the position shown in Fig. 4.

55 The arms 30 may if necessary be provided with springs 41 so as to prevent them lifting when the roller 9 contacts with roller 31.

The addressing machine is now ready for operating.

60 On turning the handle 8 the reciprocating pusher member advances the lowermost stencil card 40 to its printing position in the slideway 3 beneath rollers 9 and 12 and during this positioning of the stencil card the

segmented inking roller 9 is in contact with the roller 31 and thereby rotation of the rollers 32 and 33 is effected. An envelope is now placed on the sliding platform 4 and a movement of the lever 5 to the right positions said envelope below the stencil card. Further movement of the operating handle 70 8 causes the segmented feed roller 12 to grip the envelope and the stencil card between it and the segmented roller 9 so that the ink therefrom is forced through the perforations of the stencil and an imprint appears upon 75 the envelope in imitation of typewritten matter.

With an inking device or attachment of the nature herein described frequent application of ink from the container is avoided 80 as a few turns of the handle 39 is usually all that is necessary, and in some cases recently used stencils may be printed from without any ink being required from the roller 31 which can be moved out of contact with the 85 roller 9 by movement of the lever 37 into the position shown in Fig. 2.

It is to be understood that the inking device or attachment may be applied to varying 90 types of addressing machines wherein perforated stencils are employed, and the particular machine briefly described herein may be taken as being a fair example of its class.

A suitable dust or dirt proof cover may be 95 provided to enclose the working parts of the machine.

Having thus described my invention what I desire to secure by Letters Patent of the United States is as follows:—

100 1. In a printing machine, a frame including standards, movable arms, distributing rollers mounted on the arms, a felt covered roller normally contacting with one of the ink distributing rollers, a movable ink container carrying a wick adapted to contact with the felt covered roller to deliver ink thereto, a cam adapted to contact with one of the arms for moving the arms vertically to bring the felt covered roller into and out 105 of contact with the wick, and means for moving the ink container vertically.

110 2. In a printing machine, a frame including standards, movable arms, distributing rollers carried by the movable arms, means for rotating the rollers, a spacer bar between the movable arms, a sleeve, a spacer bar mounted in the sleeve and having a cam, said cam adapted to contact with the spacer bar for moving the rollers vertically, a segmental inking roller adapted to collect ink from the rollers, and a movable ink container adapted to deliver ink to one of said rollers.

115 In testimony whereof I have signed my name to this specification.

L. M. BARMAN.
